COMBINED GARMENT AND TRASH BAG

Robert T. Crew, 3871 Gadsden Road 32207, and Odean F. George, 6926 Cherbourg Ave. N. 32205, both of Jacksonville, Fla.

Filed July 6, 1970, Ser. No. 23,848

Term of patent 14 years

Int. Cl. D9—05

U.S. Cl. D9—350

FIG. 3

FIG.1

FIG. 2

FIG. 4

FIG. 5

FIG. 6

FIG. 1 is a front elevational view of a combined garment and trash bag showing our new design wherein the neck is straight;

FIG. 2 is a right side view thereof;

FIG. 3 is a left side view thereof;

FIG. 4 is a top plan view thereof;

FIG. 5 is a bottom view thereof;

FIG. 6 is a front elevational view in inverted position of a modification of the design of FIG. 1 wherein the neck is tapered.

We claim:

The ornamental design for a combined garment and trash bag, substantially as shown and described.
